UNITED STATES PATENT OFFICE.

JOSEPH H. PIERCE, OF CHICAGO, ILLINOIS.

FEEDING MECHANISM FOR CORN-HUSKERS.

1,160,088.

Specification of Letters Patent.

Patented Nov. 9, 1915.

Original application filed September 18, 1905, Serial No. 278,969. Divided and this application filed March 31, 1913. Serial No. 757,813.

To all whom it may concern:

Be it known that I, JOSEPH H. PIERCE, a citizen of the United States, residing at Chicago, in the county of Cook and State 5 of Illinois, have invented certain new and useful Improvements in Feeding Mechanism for Corn-Huskers, of which the following is a specification.

My invention relates to corn huskers in 10 general, but is especially directed to machines of that character which are used to operate upon ears of green corn.

My novel and improved form of machine feeds ears of corn successively to a conveyer 15 in which they are clamped in place and operated upon as follows: Each ear after being fed to the conveyer is thrust longitudinally against a stationary knife to split the protruding piece of stock up to the butt of the 20 ear, this operation positioning the ear which is subsequently cut off at its base by a circular saw revolving adjacent to the conveyer thus removing the split pieces of stock and cutting through the husks. Another knife 25 is provided for each ear which severs the top or silk thereof, the knife being caused to cut by the operation of its rotating support engaging a fixed cam. The ear is then forced longitudinally between a plurality of 30 converging spring knives so that its husks are shredded or slit their full length, and the ear is freed from the knives and falls from the machine.

In order to remove any portion of the 35 husks which have a tendency to cling to the knives or to become bunched about them, I provide a cleaner consisting of two rapidly revolving arms which rotate close to the knives and knock any remnants of husks 0 therefrom.

The particular features of the machine which form the subject matter of the present application, which is a division of my application Ser. No. 278,969, filed September 18, 5 1905, are the feeding means by which the ears of corn are automatically supplied to the machine to be operated upon by the husking and butt cutting mechanism.

In the accompanying drawings forming a part of the specification and upon which is based the following detailed description, is shown by way of illustration, one form of my improved feeding means, it being understood that various modifications in form and

arrangement may be made without departure from the invention as claimed.

In the drawings: Figure 1 is a front elevation of the machine; Fig. 2 is a fragmentary view in side elevation showing the feeding mechanism on an enlarged scale; and Fig. 3 is a detail of the same in perspective.

The description of those parts of the machine which sustain a co-operative relation only to the present invention will be in general terms, reference being had for an understanding of the details of construction to said parent application, the patent upon which, it is intended, shall issue concurrently herewith.

The machine frame consists of upright 70 members and horizontal connecting members with suitable braces. Across the top of the frame is mounted a shaft 11 rotating in bearings 12, the right hand end of the shaft as shown in Fig. 1 being supplied with a 75 sprocket wheel 13 connected by a sprocket chain to a similar wheel fastened to the shaft 14 lying to the rear of the shaft 11 and suitably journaled in the frame. Also keyed to the shaft 14 is a driving pulley 15 80 which operates the entire mechanism of the machine. On this same end of the shaft 11 is a smaller sprocket wheel 16 connected by the chain 17 with a comparatively large sprocket wheel 18 keyed to the outer end of 85 a lower shaft 19 on which is mounted a rotary conveyer 20.

Upon the left hand end of the shaft 11 I provide a pulley 21 arranged to drive the pulley 22 by means of a belt 23. The pulley 22 is fixed upon one end of the jack shaft 24 while upon the opposite end thereof is mounted a circular saw 25 revolving in proximity to the rotary conveyer 20. Connecting the shaft 24 with the lower shaft 26 95 is a cross belt 27 passing over pulleys 28 and 29 on the shafts 24 and 26 respectively, the latter being supplied at its inner end with cleaner arms to discharge husks which may accumulate about the husking knives. 100 In order to render the rotation of the cleaner arms more uniform I mount upon the outer end of the shaft 26 a comparatively heavy balance wheel 31. It will thus be observed that the motion of the drive pulley 15 is 105 transmitted by means of the various wheels, pulleys, chains, and belts so that the conveyer, saw and the cleaner are rotated.

The conveyer, which resembles a squirrel cage, is mounted on the shaft 19 and comprises, generally speaking, end spiders having radial arms with terminal annular members 32 at the left hand end and terminal U-shaped members 33 at the right hand end, the members 32 and 33 being arranged peripherally about the conveyer and the pairs longitudinally thereof, the members of each 5 pair connected by a series of spaced longitudinally extending wires 34 forming a trough-like channel for the ears which are pushed forward in said channels by members 35 acted upon by springs 36 and rolls 10 37 traveling on cam rails 38, 39, toward the left hand end of each channel where the annulus 32 is equipped with slitting knives 15 for the removal of the husk, the movement of the ears in the channels and the action of 20 the husking devices being described in detail in my said application.

The feeding mechanism for the machine comprises an inclined chute or box 40, supporting arms 41 and 42 extending upwardly, 25 and arm 43 depending from the machine frame and fastened to the box or chute to sustain the same in place. Controlling the exit of the chute 40 is discharge plate 44, which is mounted on the frame 45 pivoted to 30 one side of the chute at the point 46 and on the opposite side of the chute at a point in alignment with point 46, the frame having an extended arm 47, as shown most clearly in Fig. 3. This plate is adapted to lift and 35 allow the discharge of an ear of corn by means of mechanism described hereinafter. Above the discharge plate 44, I provide a retarding member or plate 48 which extends transversely across the chute working in 40 slots in the sides thereof and which controls the passage of the ears in the chute. Retarding member 48 comprises a frame consisting of two transverse portions 49 and 50 connected at one end by the strip 51, and at 45 the other end a link 52 rigidly connects the end of bar 50 to an upturned lug 53 integral with strip 49, the whole frame being supported on two arms 54 of which only one is shown in Fig. 3, the same being pivoted at 50 point 55 on one side of the chute 40. Integral with or attached to strip 50, is catch 56. The feeding mechanism also comprises 55 a slide plate 57 reciprocating in guides 58 on the upper surface of the box or chute, 60 the slide having pivoted thereto at its lower end the feed plate 58 by means of hinges 59, a spring 60 fastened to slide 57, operating on feed plate 58 to hold the same depressed. Attached to the upper end of the slide is 65 member 61, which has pivoted thereto at its lower end rod 62 connecting it with the arm 47 which actuates the discharge plate 44. Connecting arm 47 and the part 52 of the retarding frame is coiled spring 63, which 65 tends to retain the retarding plate in posi-

tion to prevent the passage of the ears in the chute. To the frame piece 64 is pivoted lever 65 at the point 66, one end of said lever being attached to the slide 57 by link 67, pivoted to the end of lever 65 and to the strip 68 fastened to the upper end of the slide. Spring 69 is connected at one end to a fixed portion of the lower part of the frame, rod 72 connecting the upper end of said spring to the end 73 of lever 65. The lower end of operating lever 74 (Fig. 3) is pivoted to the frame of the machine and said lever is pivoted to one end of the connecting link 76 at the point 77, the other end of said piece 76 being pivoted at 78 to the lever 65 near its pivot 66. The upper free end of lever 74 which is pulled inwardly by means of spring 69 acting through the end 73 of lever 65 rides over the upper ends of the U-shaped members 33. As the conveyer operates these upper ends of members 33 pass under the free end of lever 74 causing the same to move upwardly and when the ends have passed from beneath the lever the same move downwardly due to the action 90 of spring 69. It will be obvious then that as the conveyer rotates lever 74 is constantly oscillating to a limited extent, and it is by means of this oscillation that the feeding mechanism of the device is operated. To 95 the upper end of member 61 is pivoted at the point 79 a latch lever 80, said lever being pulled downwardly by the spring 81 which joins it to the connecting rod 62. Latch lever 80 is provided at its end with a hook shaped portion 82, adapted to engage catch 56 on the retarding frame 48. Attached to the frame member 43 is a pin 83 over which rides the inclined cam portion 84 of the latch lever 80. As the slide 57 moves downwardly 100 or advances, lever 80 rides over pin 83, at length engaging catch 56, and on the backward or reverse movement of slide 57, latch 82 remains engaged with catch 56 thereby raising the retarding plate or frame 48, 105 allowing the passage of an ear of corn. When the slide has moved back to some extent, the cam portion 84 rides upon pin 83 whereupon the hook 82 is released from catch 56 so that the retarding member or 110 plate assumes its original position under the influence of spring 63.

The operation of this machine is as follows: The driving of pulley 15, by means of an external source of power rotates shaft 14, and by means of the sprocket wheels together with the connecting chain, shaft 11 receives its rotary motion. Shaft 19 which bears the conveyer receives its motion from shaft 11, by means of the sprocket wheels 16 and 18 and the connecting chain 17. Shaft 11 transmits power to shaft 24 by means of pulleys 21 and 22 and belt 23, these connections furnishing rapid motion for the circular saw 25, and in order to rotate shaft 11

26 with its cleaning arms 30, the crossed belt 27 is passed over the pulleys 28 and 29, balance wheel 31 producing a uniform motion of parts.

5 The chute 40 having been supplied with the ears of corn with their stock ends all at one side, the feeding mechanism is operated in this manner: The rotation of the conveyer causes the oscillation of lever 74 whose outer end rides over and is released from the upper ends of U-shaped members 33. This oscillating motion of lever 74 is communicated by means of connecting piece 76 to lever 55, the latter causing the reciprocation of slide 57. The advance of downward movement of slide 57 lifts discharge plate 44 by means of connecting parts 61, 62, 47 and 45. As the slide still further advances, the pivoted spring 20 pressed feed plate 58 strikes the ear, if it has not been already discharged into its receptacle by the lifting of plate 44, and forces the same into said receptacle, the movement of the parts being so timed that 25 the receptacle will be opposite the discharge end of the feeding mechanism at the instant the ear is released and pushed therefrom. During this forward or advance movement of the slide, the latch lever 80 engages catch 56, and on the backward or reverse movement of the slide, the discharge plate is lowered so as to close the exit of the chute, the retarding plate or frame 48 is 30 lifted by means of the movement of the latch and catch so as to allow an ear to roll down the chute against the discharge plate to replace the one which has just been discharged into its receptacle. As the slide still continues on its backward movement, 35 latch lever 80 riding over its coöperating pin 83 and held thereagainst by spring 81, at length reaches the position where the cam surface 84 comes in contact with pin 83, thereby lifting the latch lever so that its hook end 82 is freed from catch 56, whereupon the retarding plate or frame 48 quickly returns to its normal position under the influence of spring 63. On the next forward movement of the slide the ear which 40 has just been described as rolling down the chute to the discharge plate, would be forced into the next receptacle.

At the time the ear is placed in its receptacle, the member 35 is at its extreme limit of movement to the right as shown in Fig. 1. As soon as the ear is deposited in the receptacle or trough roller 37 passes off of the end of cam rail 38, and due to the release of the springs 36, the members 35 quickly slide to the left, the silk end of the corn passing into the funnel shaped member 35 and protruding through the annulus 32. The sliding movement of member 35 under the action of springs 36 causes the stock end of the ear to project from the end

of the conveyer, where it is subjected to the action of the splitting knives and butt cutting saw.

As the rotation of the conveyer is continuous and the feeding mechanism is constantly supplying ears to the troughs as they are presented thereto, the husking operation is without interruption.

While I have herein shown and described what I deem preferred embodiments of the invention, I am aware that modifications can be made therein without departing from the substance of my invention and I do not, therefore, limit the invention to the details shown and described except in so far as such details are made the subject matter of specific claims.

I claim:

1. In a machine of the character described, a feeding mechanism comprising the combination of a chute, a slide, and means for feeding ears of corn one at a time along said chute comprising a yieldingly mounted feed plate to push an ear of corn from said chute as said slide moves forward and to ride over the next ear as the slide returns, said feed-plate being hinged to said slide at one edge, its opposite edge being free, substantially as described.

2. In a machine of the character described, a feeding mechanism comprising the combination of a chute, a slide, and means for feeding ears of corn one at a time along said chute comprising a spring pressed feed-plate hinged to said slide to push an ear of corn from said chute as said slide moves forward and to ride over the next ear as the slide returns, substantially as described.

3. In a machine of the character described, a feeding mechanism comprising the combination of a chute, a discharge plate to open and close the exit of said chute, and a slide adapted to reciprocate longitudinally of said chute to push the ears of corn from said chute when the discharge plate opens the exit thereof, the elements of the feeding mechanism arranged to operate in alternation and in timed sequence to effect an intermittent feed, substantially as described.

4. In a machine of the character described, a feeding mechanism comprising the combination of a chute, a discharge plate to open and close the exit of said chute, a slide and a feeding plate hinged to said slide to push the ears of corn from said chute when the discharge plate opens the exit thereof, the elements of the feeding mechanism arranged to operate in alternation and in timed sequence to effect an intermittent feed, substantially as described.

5. In a machine of the character described, a feeding mechanism comprising the combination of a stationary chute, a retarding member to control the passage of the ears of corn in the chute, and a slide adapted to re-

ciprocate longitudinally of said chute to push the ears of corn from said chute, the elements of the feeding mechanism arranged to operate in alternation and in timed sequence to effect an intermittent feed, substantially as described.

6. In a machine of the character described, a feeding mechanism comprising the combination of a chute, a retarding member to control the passage of the ears of corn in said chute, a slide, and a feeding plate hinged to said slide to push the ears of corn from said chute, the elements of the feeding mechanism arranged to operate in alternation and in timed sequence to effect an intermittent feed, substantially as described.

7. In a machine of the character described, a feeding mechanism comprising the combination of a chute, a discharge plate opening and closing the exit of said chute, a retarding member controlling the passage of the ears of corn in said chute, and a slide to push the ears of corn from said chute, the elements of the feeding mechanism arranged to operate in alternation and in timed sequence to effect an intermittent feed, substantially as described.

8. In a machine of the character described, a feeding mechanism comprising the combination of a chute, a discharge plate to open and close the exit of said chute, a retarding member to control the passage of the ears of corn in said chute, a slide and a feed plate hinged to said slide to push the ears of corn from said chute, the elements of the feeding mechanism arranged to operate in alternation and in timed sequence to effect an intermittent feed, substantially as described.

40 9. In a machine of the character described, a feeding mechanism comprising the combination of a chute, a movable retarding plate provided with a catch, said plate controlling the passage of ears of corn in said chute, a slide, a latch movable with said slide and adapted to engage said catch on the forward movement of said slide and lift said retarding plate on the backward movement of said slide, and means to disengage said latch from said catch, substantially as described.

10. In a machine of the character described, a feeding mechanism comprising the combination of a chute, a pivoted spring pressed retarding plate provided with a catch, said plate controlling the passage of the ears of corn in said chute, a slide, a latch movable with said slide and adapted to engage said catch on the forward movement of said slide and lift said retarding plate on the backward movement of said slide, and means to disengage said latch from said catch, substantially as described.

11. In a machine of the character described, a feeding mechanism comprising the combination of an inclined chute, a pivoted discharge plate to open and close the exit of said chute, a retarding member to control the passage of the ears of corn in said chute, and means to push the ears of corn from said chute, the elements of the feeding mechanism arranged to operate in alternation and in timed sequence to effect an intermittent feed, substantially as described.

12. In a machine of the character described, the combination of a traveling conveyer provided with a plurality of receptacles, each adapted to receive an ear of corn, a feeding mechanism to supply ears to said receptacles, a movable support for one end of the ear in each receptacle, means to move said supports to one end of their travel, and means to move each support after an ear is in its receptacle to support the end thereof, substantially as described.

13. In a machine of the character described, the combination of a traveling conveyer provided with a plurality of receptacles, each adapted to receive an ear of corn, a feeding mechanism to supply ears to said receptacles, a movable support for one end of the ear in each receptacle, cam means to move said supports to one end of their travel, and spring means to move each support after an ear is in its receptacle to support the end thereof, substantially as described.
